POWER CONTROL FOR A PNEUMATIC TUBE CARRIER SYSTEM

Clarence W. Grover, Highland Park, Mich., assignor to Grover Company, Detroit, Mich., a corporation of Michigan

Application October 19, 1933, Serial No. 694,233

10 Claims. (Cl. 243—12)

This invention relates to a power control for a pneumatic tube carrier system. This invention relates more particularly to a power control for a pneumatic tube carrier system of the minimum flow type. The minimum flow type carrier system is old and well-known, and is characterized by the fact that a small flow of air is at all times maintained through the system and that the maximum power is obtained upon the introduction of a carrier into the tube through a power control device which throws on the full power which drives the carrier through the system. After the carrier reaches its destination and is discharged the full power must be turned off and the minimum flow again restored. This invention relates particularly to that portion of the power control apparatus which reduces the full power or flow of air to the minimum power or flow as soon as the carrier reaches its destination or whenever the velocity of the carrier exceeds an arbitrary or desirable maximum.

It is also broadly old in the art to reduce the system from a full power status to a minimum power or minimum flow status by utilizing the increased velocity or kinetic energy of the air flowing through the tube brought about by the discharge of the carrier. It is an object of this invention to produce an improved type of power control which is actuated by the increased velocity of the air flow caused by the removal of the load, that is, the discharge of the carrier from the tube, which is quick acting, reliable, simple, durable, and appreciably cheaper to manufacture than any power control which has heretofore been suggested or placed upon the market.

In the drawing:

Figure 1 is a lay-out of a conventional form of pneumatic tube carrier system.

Figure 2 is a vertical section through the power control when the system is inoperative and a minimum flow of air maintained.

Figure 3 is a vertical section through the power control showing the position of the various parts immediately subsequent to the discharge of the carrier and as the balanced valves are about to close.

Figure 4 is a section along the line 4—4 of Figure 3.

Referring to Figure 1 there is shown a conventional form of pneumatic tube carrier system comprising a vacuum tank 1, power control 2, and stations 3 and 4 which are connected by the power tubes 5 and 6. It is understood, of course, that whether the system is operated by pressure or

suction, the apparatus functions the same and one is the equivalent of the other. The air flow is from station 3 through pipe 5 to station 4, and from station 4 through pipe 6 back to station 3 and then through the control 2 to the vacuum tank 1. The power control 2 is positioned between the vacuum tank 1 and the return tube 6. Hence, referring to Figure 2 the inlet port of the control may be designated 7 and the outlet port, which leads to the vacuum tank, designated 8.

The power control comprises a casing 10 which encompasses a main air chamber 11. The main casing 10 is provided with an auxiliary casing 12 which in turn encompasses the outlet chamber 13. The casing 12 is provided with the outlet ports 14 and 15 which are controlled by the valves 16 and 17 respectively. The valves 16 and 17 are known as balanced valves, that is, the valve 16 is on the windward side of the port 14 whereas the valve 17 is on the leeward side of the port 15. In other words, the valve 16 is without the outlet chamber 13 and the valve 17 is within the chamber 13. Thus, when the valves are either opened or closed the pressure on the valve 16 tending to close, or to hold closed, the valve 16 counterbalances the pressure on the valve 17 tending to open, or to hold open, the valve 17. The valves 16 and 17 are mounted in spaced relation upon the sleeve 18 which in turn is slidably mounted upon the shaft 19. One end of the shaft 19 is journaled in the adjusting screw 20 which is threaded in the opening 21 in one wall of the casing 10. The screw 20 is provided with an annular collar 22 and adjusts the tension of the coil spring 23 which is mounted between the valve 16 and the collar 22. The other end of the shaft is threaded into the spider 24 which extends across the opening 25 in the opposite wall of the casing 10.

The valves 16 and 17 may be controlled by any suitable type of pneumatic. By way of description the opening 25 in the wall of the casing 10 is closed by a pneumatic which herein takes the form of a flexible leather diaphragm 26 which is secured to an end of the sleeve 18 by the opposed nuts 27 and 28 threaded over the sleeve 18. Preferably the adjusting screw 20 is adjusted so that the maximum force of the coil spring 23 when collapsed is slightly less than the power of the diaphragm 26 created by the difference in pressure between the inside and the outside of the casing 10 when the balanced valves are thrown open and full power is applied to tubes 5 and 6.

Since this power control device is adapted for use in a pneumatic tube carrier system of the

minimum flow type, such minimum flow may be obtained in any of the well-known ways as by providing the inner casing 12 with a small outlet port 29 and a screw valve 30 with a conical end 5 for regulating the amount of air permitted to flow through the opening 29.

The operation of the power control is as follows: Assuming the balanced valves 16 and 17 are in closed position, as shown in Figure 2, and 10 a minimum flow of air, as permitted by the port 29 and regulating valve 30, is flowing through the tubes 5 and 6 and inlet 7 into the casing 10 and through the port 29 to the chamber 13 and thence through the outlet 8 to the vacuum tank 1. 15 If a carrier is now placed in the inlet end of the tube 5, this carrier serves as a piston and blocks the flow of atmospheric air into the tube 5. Hence, the pressure is gradually decreased in the chamber 11, that is, the amount of vacuum increases and in a very short time outside atmospheric pressure on the diaphragm 26 becomes sufficiently greater than the pressure in the chamber 11 plus the force of the coil spring 23 to move the sleeve 18 with the valves 16 and 17 20 toward the left, or to open position, upon the guide 19, as shown in Figure 3. At this time, since ports 14 and 15 are now open, a maximum flow of air through the power control is permitted and the full power or suction is applied 25 to the carrier thus drawing the same through the tube 5 until discharged through the hinged valve outlet of the tube 5 at the station 4. At this time the valves 16 and 17 are still open and a full flow of air is passing through the tubes 5 30 and 6, through the control 2 into the tank 1 thus causing a waste of power. Hence, it is desirable 35 that the valves 16 and 17 be thrown to closed position as soon as the carrier is discharged.

To this end the casing 10 is provided with a 40 guide rod 31, one end of which is journaled in the adjusting screw 33. The guide rod 31 has 45 slidably mounted thereon the slide 34. A coil spring 35 is threaded over the rod 31 between the inner end of the adjusting screw 33 and the 50 slide 34. The slide 34 is provided on the upper side with the inclined vane 36 in the form of a flat inclined surface and on the lower side with the depending valve 37. The valve 37 is provided with an embossed opening 38 which has a nice 55 sliding fit with the sleeve 18.

The tension of the spring 35 can be adjusted by the screw 33 so that the force exerted against the slide 34 is sufficient to hold the slide with its 60 vane 36 and valve 37 in the open position shown in Figure 2 at all times, except when the velocity of the air through the inlet opening 7 is increased beyond the normal rate of flow. Such increase in velocity occurs when the carrier is discharged, or when the speed of the carrier in the tube exceeds a predetermined rate as, for instance, when 65 the carrier drops where the tube extends vertically an appreciable distance.

The guide rod 31 is threaded at one end and 70 provided with an adjusting nut 39 which can be adjusted back and forth along the rod 31 to vary the position of the valve 37 when open relative to the port 15.

In operation, assuming that the balanced valves 75 16 and 17 are in the open position shown in Figure 3, the vane 36 and the valve 37 are in open position as shown in Figure 2, and the carrier has just been discharged at the station 4: At this time, the load having been removed from the line, the velocity of air passing through the inlet 7 is increased or speeded up so that the energy of

the air striking the inclined vane 36 forces the slide 34 to the left compressing the coil spring 35 and moving the valve 37 to the position shown in Figure 3 so that it closes the port 15. Since the pressure in the vacuum tank 1, which is less than atmospheric pressure, is constant, as soon as the port 15 is closed the velocity of the flow of air through the port 14 is increased which in turn increases the closing force against the valve 16. Further, as above explained, when the balanced valves 16 and 17 are open the force of the collapsed coil spring 23 plus the pressure in the chamber 11 is but slightly less than the atmospheric pressure upon the diaphragm 26. Then too, before the valve 37 is thrown to closed position, the pressure of the air flowing through the inlet 15 exerted against the valve 17 and tending to hold the same open is about equal to the pressure of the air flowing through the opening 14 exerted against the valve 16 and tending to close the valve 16. Hence, as soon as the valve 37 closes the port 15, owing to the force exerted against the vane 36 caused by the increased velocity of the air upon the discharge of the carrier, this pressure upon the valve 17 which tends to hold the valve open is now removed thus throwing the balanced valves out of balance. This cutting off of the pressure on the valve 17 and the additional closing force which is exerted on valve 16 by the speeding-up of the air flowing through the port 14, throw the valves 16 and 17 out of balance and they move to closed position as shown in Figure 2.

As soon as the valves 16 and 17 close the ports 14 and 15, the flow of air through the tubes 5 and 6 and the inlet 7 is reduced to the minimum flow, and since the speed of the air is greatly decreased, the force now exerted upon the vane 36 is less than the force of the coil spring 35 whereupon the slide 34, vane 36 and valve 37 are moved to the right or to open position thus placing the vane in the position shown in Figure 2 ready for operation as soon as another carrier is discharged from the tube.

It is, of course, understood that the entire action of this power control is almost instantaneous and encompasses at most but a very few seconds.

It is evident from the above description that there is herein shown a power control for a pneumatic tube carrier system of the balanced valve type utilizing the increased speed of the air flow immediately following the removal of the load or discharge of the carrier from the tube which is characterized in that the speeded up air flow causes an auxiliary valve to close one of the air ports thereby throwing out of balance the various forces acting upon the valves so that the closing forces exceed the opening forces and thus cause the valves to close.

What is claimed is:—

1. A power control for a pneumatic dispatch system of the minimum flow type having a transmission conduit and a power source for creating a propelling air current through the conduit, comprising a pair of ports permitting air flow between the conduit and the power source, a pair of balanced valves for controlling the ports, and auxiliary valve means normally open as when a carrier is being transmitted through the conduit or when a minimum flow of air is permitted, said means being actuatable to close one of said ports by an increased flow of air through the conduit such as occurs when the balanced valves are open and the carrier is discharged whereby the valves

- are thrown out of balance and moved to closed position.

2. A power control for a pneumatic dispatch system of the minimum flow type having a transmission conduit and a power source for creating a propelling air current through the conduit, comprising an outer casing and an inner casing, a pair of ports permitting communication between the outer and the inner casings, a pair of balanced valves for closing the said ports, one of said valves being positioned within the outer casing and the other of said valves being positioned within the inner casing, and auxiliary valve means for controlling one of said ports normally open as when a carrier is being transmitted through the conduit or when a minimum flow of air is permitted and actuatable to close one of said ports by an increased flow of air through the conduit such as occurs when the balanced valves are open and the carrier is discharged whereby the valves are thrown out of balance and moved to closed position.

3. A power control for a pneumatic dispatch system of the minimum flow type having a transmission conduit and a power source for creating a propelling air current through the conduit, comprising an outer casing and an inner casing, a pair of ports permitting communication between the outer and the inner casings, a pair of balanced valves for closing the said ports, one of said valves being positioned within the outer casing and the other of said valves being positioned within the inner casing, an auxiliary valve for controlling one of said ports, and a vane actuatable by an increased flow of air through the conduit such as occurs when the carrier is discharged for closing the said auxiliary valve whereby the balanced valves are thrown out of balance and moved to closed position.

4. A power control for controlling the flow of air between the transmission conduit and the power source of a pneumatic dispatch system of the minimum flow type comprising in combination a pair of ports between the power source and the conduit, a pair of balanced valves for the said ports, a pneumatic exposed on one side to atmospheric pressure and on the other side to the pressure obtaining in the conduit, said pneumatic being operatively connected to the valves for opening the same upon the introduction of a carrier into the transmission conduit, resilient means for counterbalancing the said pneumatic, one of said balanced valves being on the leeward side of its port and the other being on the windward side of its port, an auxiliary valve for one of said ports normally in open position as when a carrier is being transmitted through the conduit or a minimum flow of air is permitted through the conduit, and means for closing said valve actuatable by an increased flow of air through the conduit such as occurs when the carrier is discharged from the conduit whereby the balanced valves are thrown out of balance and moved to closed position thereby cutting off the full flow of air.

5. A power control for controlling the flow of air between the transmission conduit and the power source of a pneumatic dispatch system of the minimum flow type comprising in combination a pair of ports between the power source and the conduit, a pair of balanced valves for the port, one of said valves being on the leeward side of the first port and the other being on the windward side of the second port, a pneumatic ex-

posed on one side to atmospheric pressure and on the other side to the pressure obtaining in the conduit, said pneumatic being operatively connected to the valves for opening the same upon the introduction of the carrier into its transmission conduit, resilient means for counterbalancing the said pneumatic, auxiliary valve means on the windward side of the first port normally in open position as when a carrier is being transmitted through the conduit or a minimum flow of air is permitted through the conduit, said auxiliary valve means being actuatable to close the first of said ports by an increased flow of air through the conduit such as occurs when the carrier is discharged from the conduit whereby the balanced valves are thrown out of balance and moved to closed position thereby cutting off the full flow of air.

6. A power control for controlling the flow of air between the transmission conduit and the power source of a pneumatic dispatch system of the minimum flow type comprising in combination a pair of ports between the power source and the conduit, a pair of balanced valves for the ports, one of said valves being on the leeward side of the first port and the other being on the windward side of the second port, a pneumatic having one face exposed to atmospheric pressure and the other to the pressure obtaining within the conduit, said pneumatic being operatively connected to the valves for opening the same upon the introduction of the carrier into its transmission conduit, resilient means for counterbalancing the said pneumatic, an auxiliary valve positioned on the windward side of the first port normally in open position as when a carrier is being transmitted through the conduit or a minimum flow of air is permitted through the conduit, and vane means operatively connected to the said valve actuatable by an increased flow of air through the conduit such as occurs when the carrier is discharged from the conduit to close the said valve whereby the balanced valves are thrown out of balance and moved to closed position.

7. A power control for controlling the flow of air between the transmission conduit and the power source of a pneumatic dispatch system of the minimum flow type comprising in combination a pair of ports between the power source and the conduit, a pair of balanced valves for the said ports, a pneumatic exposed on one side to atmospheric pressure and on the other side to the pressure obtaining in the conduit, said pneumatic being operatively connected to the valves for opening the same upon the introduction of a carrier into the transmission conduit, resilient means for counterbalancing the said pneumatic, one of said balanced valves being on the leeward side of its port and the other being on the windward side of its port, an auxiliary valve for one of said ports normally in open position as when a carrier is being transmitted through the conduit or a minimum flow of air is permitted through the conduit, and means for closing said valve actuatable by an increased flow of air through the conduit such as occurs when the carrier is discharged from the conduit whereby the balanced valves are thrown out of balance and moved to closed position thereby cutting off the full flow of air, and means for returning the auxiliary valve and aforementioned actuating means to their normal open position as soon as the balanced valves are closed.

8. A power control for controlling the flow of air between the transmission conduit and the power source of a pneumatic dispatch system of the minimum flow type comprising in combination a pair of ports between the power source and the conduit, a pair of balanced valves for the said ports, one of said valves being on the leeward side of the first port and the other being on the windward side of the second port, a pneumatic exposed on one side to atmospheric pressure and on the other side to the pressure obtaining in the conduit, said pneumatic being operatively connected to the valves for opening the same upon the introduction of the carrier into the transmission conduit, resilient means for counterbalancing the said pneumatic, an auxiliary valve on the windward side of the first port normally in open position as when a carrier is being transmitted through the conduit or a minimum flow of air is permitted through the conduit, and a movable vane inclined relative to the direction of the flow of air through the conduit operatively connected to the auxiliary valve and actuatable by an increased flow of air through the conduit such as occurs when the carrier is discharged from the conduit to close the first port whereby the balanced valves are thrown out of balance and moved to closed position. 80

9. A power control for controlling the flow of air between the transmission conduit and the power source of a pneumatic dispatch system of the minimum flow type comprising in combination a pair of ports between the power source and the conduit, a pair of balanced valves for the said ports, one of said valves being on the leeward side of the first port and the other being on the windward side of the second port, a pneumatic exposed on one side to atmospheric pressure and on the other side to the pressure obtaining in the conduit, said pneumatic being operatively connected to the valves for opening the same upon the introduction of the carrier into the transmission conduit, resilient means for counterbalancing the said pneumatic, an auxiliary valve on the windward side of the first port normally in open position as when a carrier is being transmitted through the conduit or a minimum flow of air is permitted through the conduit, a guide support for the said auxiliary valve, an inclined vane guided on the said support and operatively connected to the said auxiliary valve, the said inclined vane being actuatable by an increased flow of air through the conduit such as occurs when the carrier is discharged from the conduit to close the said auxiliary valve whereby the balanced valves are thrown out of balance and moved to closed position thereby cutting off the full flow of air, and resilient means for returning the said auxiliary valve and vane to their initial normal open position as soon as the said balanced valves are closed. 120
